UNITED STATES PATENT OFFICE.

FERDINAND PHILIPS, OF PHILADELPHIA, PENNSYLVANIA.

WHEEL AND WHEEL-RIM.

SPECIFICATION forming part of Letters Patent No. 743,098, dated November 3, 1903.

Application filed October 27, 1899. Serial No. 734,919. (No model.)

To all whom it may concern:

Be it known that I, FERDINAND PHILIPS, a subject of the Emperor of Germany, residing in the city and county of Philadelphia, in the 5 State of Pennsylvania, have invented certain new and useful Improvements in Wheels and Wheel-Rims, of which the following is a true and exact description, reference being had to the accompanying drawings, which form a 10 part thereof.

My invention relates to the construction of wheels and wheel-rims, especially rims of sheet metal, having particularly in view the formation of rims for pulley-wheels, my prime 15 object being to provide a wheel-rim built up of segments which will be at once strong, true, and of easy and cheap construction.

The essential feature of my invention in the construction of the rim consists in forming a rim of sheet metal folded together intermediate of its edges to form an inwardly-extending two-ply flange and folded outwardly from the top edges of the two-ply flange to form the face of the wheel. The 25 edges of the folded plate are also preferably folded inward to form strengthening ribs or flanges, and the plate having the T-shaped cross-section described is curved in the plane of its central flange to the desired curvature 30 of the wheel-face. The central flange of the wheel-rim section constructed as above noted serves for the attachment of the spokes of the wheel-center and also serves to stiffen and make permanent the curvature of the 35 face of the rim, the edge flanges also serving the purpose of stiffening and making permanent the curvature.

While my new rim can be used with hub and spoke constructions of various kinds, I 40 have especially designed for use with the T-shaped rim-sections a cast-iron wheel-center the spokes of which are bifurcated at the ends to permit the entrance between its separated end lugs of the inwardly-extending 45 flange of the rim, which is secured to the spokes by rivets passing through the lugs and flange.

Reference being now had to the drawings, in which my invention is illustrated, Figure 50 1 is a sectional view of a split pulley having my improved rim and cast-iron center, the section being taken as on the line 1 1 of Fig.

2: Fig. 2 is an edge view of the split pulley with the edge cut away on the line 2 2 of Fig. 1: Fig. 3 is an enlarged view of the under 55 side of the joint or union formed between two abutted rim-sections. Fig. 4 is an edge view of the joint shown on the same scale as Fig. 3. Fig. 5 is an edge view taken on the section-line 5 5 of Fig. 3. Fig. 6 is a perspective view showing the folding of the end of the plate forming the joint as represented in Figs. 3, 4, and 5. Fig. 7 is a perspective view showing a modified manner of folding the plate at its end. Fig. 8 is a view of the 60 inside of the joint formed by two abutted rim-sections, the joint here being of a modified and different character. Fig. 9 is an edge view of the modified joint shown as on the section-line 9 9 of Fig. 8, and Fig. 10 is a 65 view illustrating a convenient way of forming the joint when the rim-sections are used in making up the face of a solid pulley.

A A indicate the hub-sections of the split pulley, said hub-sections being formed with 70 outwardly-extending perforated lugs A' and with radial spokes, (indicated at A² A², &c.)

A³ indicates enlargements at the end of the spokes, formed with central slots, as indicated at a³, to receive the central flange of the rim. 80

B B indicate bolts, by means of which the hub-sections are secured together.

C C indicate rivets, by which the lugs of the enlarged spoke ends A³, separated by the slots a³, are firmly secured to the web of the 85 rim.

D D indicate rim-sections constructed in accordance with my invention. They are formed of sheet-metal strips folded together intermediate of their edges, so as to form inwardly-extending circumferential two-ply folds, (indicated at D' D').

D² D² are outward folds of the metal extending from the top edges of the flange-folds D' and forming the face of the pulley or 90 wheel.

D³ D³ indicate inwardly-folded edges of the plates, forming inwardly-extending flanges, as shown. As clearly shown in Figs. 1, 2, and 10, the central flanges or ribs D' D' fit into the slots a³ in the ends of the spokes and are secured in place by rivets, (indicated at C.)

While I have shown my new cast-metal hub and spokes, it will be understood that I do

not confine myself to this character of wheel center and spokes except where the same are expressly claimed, but may use in connection with my rim-sections any convenient hub and 5 spoke construction which is adapted to be secured to a flange, such as D' D'.

The rim-sections of my wheel are bent in the plane of the flange D' D' and to the curvature of the desired wheel-rim, the ends of the 10 rim-sections being abutted together, and it is preferable that the abutted edges should be firmly locked in place, as it will be understood that the pulley is more likely to become distorted at the joint than at other points. In 15 Figs. 3, 4, 5, and 6 I have illustrated a convenient and satisfactory way of forming the joint at the abutted ends of the rim-sections, the ends of the rim being bent inward at a right angle to the face of the rim, forming flanges, as 20 indicated at D⁴ D⁴, which of course are practically in planes radial to the center of the pulley. To make this end flange, it is of course necessary that the central rim-flange D' should be cut. Preferably I cut it away at an angle of 25 ninety degrees, so that the bevel edges, as indicated at D⁵ and d⁵, will abut together, (see Fig. 6,) the portion of the central web attached to the folds D⁴ D⁴ being indicated at d'. The ends of the rim-sections being bent to the positions 30 shown in Fig. 6 are then firmly secured together by angle-irons, as indicated at E E' E², the portion E lying against the end folds D⁴, the portions E' lying against the central flanges made up of the portions D' and d', and the portions E² abutting against the edge folds D⁵. Rivets are conveniently employed to secure the portions E' and E² of the angle-iron to the flanges of the rim, and bolts are employed, as best shown in Fig. 3, to secure the 35 plates E and flanges D⁴ together and to secure the abutted flanges in position. I have also braced the inwardly-turned folds D⁴ in 40 position by separating the web portions d' from the web portions D' by means of a straight cut, as indicated at D⁶ d⁶, and then lapping the portion d' on the portion D', as 45 indicated in Fig. 7, employing rivets to secure the lapped portions together.

In Figs. 8 and 9 I have shown an abutted 50 joint in which the rim-sections are not turned in at the ends, but are abutted against each other and secured together by angle-irons E³ E⁴, the portions E⁴ of the irons being riveted to the rim and the portions E³ riveted or 55 bolted together. The abutted joint between the rim portions is indicated at D⁷ D⁷.

Where the pulley is a solid and not a split one the joint may be made as shown in Fig. 10, in which I have partly broken away one 60 of the lugs of the head A³ on one side of the groove a³ formed in it. In this construction the two rim-sections D D form an abutted joint, as in Figs. 8 and 9, the joint being braced and the parts alined by bringing one 65 of the spokes of the pulley into alinement

with it and riveting the ends of both sections of the rim to the same spoke of the pulley.

I am aware that sheet-metal wheel-rims have heretofore been made up of separate flanged segments, two or more such segments 70 being abutted together to form the full breadth of the rim and intermediate circumferential two-ply flanges; but in all such constructions the plies of the intermediate flanges are merely in contact and only held 75 together by separate fastening device. My rim is distinguished from such prior constructions by the union of the plies of the flanges throughout their inner edge, whereby the structural strength of the flange is greatly 80 increased and the strength of the rim as a whole and also the correct alinement of the parts on each side of the flange is greatly promoted.

Having now described my invention, what 85 I claim as new, and desire to secure by Letters Patent, is—

1. A wheel-rim section consisting of a plate of sheet metal folded together at a point intermediate of its edges to form an inwardly-extending two-ply flange suitable for attachment to the spokes of the wheel and folded outward from the top edges of the flange-folds to form the face of the wheel, said folded section being curved circumferentially in a plane 95 parallel to the flange.

2. A wheel-rim section consisting of a plate of sheet metal folded together at a point intermediate of its edges to form an inwardly-extending two-ply flange suitable for attachment to the spokes of the wheel, said plate being folded outward from the top edges of the flange-folds to form the face of the wheel and again folded inward at its edges to form strengthening-ribs, said folded section being 100 curved circumferentially in a plane parallel to the flange.

3. A wheel-rim formed of plates of sheet metal folded together intermediate of their edges to form inwardly-extending two-ply 110 flanges suitable for attachment to the spokes of the wheel and folded outward from the top edges of said flanges to form the face of the wheel, the ends of said plates being bent in at right angles to form abutting faces and secured together in forming the complete rim.

4. A cast-metal wheel-center having formed integral with it, radial spokes slotted at their ends, in combination with a rim of T-shaped section formed by folding sheet metal together to form a two-ply web and outwardly from the top of the web-flange to form the face of the wheel, said rim-section having its two-ply web fitted into slots of the spoke ends and secured thereto.

FERDINAND PHILIPS.
